UNITED STATES PATENT OFFICE

REINHOLD RICHARD WAGNER, OF BERLIN-CHARLOTTENBURG, GERMANY

GAS HOLDER

Application filed August 23, 1926, Serial No. 130,865, and in Germany November 10, 1925.

My invention relates to a gas holder in which a piston, disc or like closure member reciprocates within the gas holder making a tight joint therewith.

5 According to this invention, the movable closure member is adapted to move horizontally or substantially horizontally the gas holder being situated horizontally or slightly inclined, and being of uniform vertical cross-
10 section throughout the entire portion in which the closure member moves. The capacity of the gas holder is varied by horizontal movement of the closure member.

The weight of the closure member may be
15 supported by a slide block at the lower end of the closure member, but the closure member is preferably mounted to run upon rails upon the floor of the gas holder.

The gas holder is preferably, of horse-shoe
20 or saddle shape in cross-section and the floor of the gas holder may be formed by the ground upon which the holder is built.

The floor is preferably horizontal or only
25 very slightly inclined, so that, when a liquid seal is employed for the lower edges of the movable closure member, the layer of liquid will not require considerable variation in depth from one end of the holder to the other.

30 The closure member is preferably given a rectilinear movement so that the floor of the gas holder can be made rectangular in outline. The closure member may, however, move in a curved line and may even swing at one of its edges like a door in its hinges in such a manner that the floor forms a circle, or a sector of a circle.

The necessary pressure on the gas can be
40 attained in various ways by urging the movable closure member towards the fixed end of the gas holder. To this end I may connect the movable closure member to cables which pass through the gas space and through the fixed end, being loaded at their outer ends and so arranged as to distribute the load to the movable closure member in such a manner that the load equalizes all the horizontal forces acting upon the movable closure member, namely, the air pressure, gas pressure, friction and inertia.

The advantages derived from the present invention are that the movable closure member cannot fall, because it runs upon the floor. The gas holder can be several hundred yards in length and considerable capacity can therefore be obtained without requiring a high gas holder and the specific floor surface load due to wind pressure and weight moreover is kept low. The gas holder can be increased in size without danger while in use. The end of the gas holder opposite to its closed end can be quite open, thus rendering it impossible for an explosive mixture of gas and air to accumulate.

55 One embodiment of the improved gas holder is illustrated in the accompanying drawings whereon:—

Fig. 1 shows the new holder partly in longitudinal section and partly in side view.

Fig. 2 is a horizontal sectional plan view
60 of the gas holder.

Fig. 3 is a cross-section looking towards the movable end, and Fig. 4 is an end view looking on the fixed end of the gas holder.

65 In the drawing, 1 designates the gas holder shell which is supported in a skeleton framework 2 and closed at one end by the end wall 11. The movable end consists of a skeleton frame 3 carrying gas-tight metal cover plating 4. The frame 3 is supported by wheels 5 resting upon rails 6 which are laid upon the floor 7 of the gas holder. Cables 9 are secured to the movable end at 8 and extend through the gas space and passing through apertures 10 in the end wall 11 into the partially closed boxes 12, where the cables pass around sheaves 13 and 14 which dip into a liquid seal 15. A tongue 16 projects down into the liquid 15 so that gas cannot escape through the apertures
70 10.

75 The gas enters the gas space G of the gas holder by way of the inlet E and is delivered through the outlet A. On the outer side of the movable end is an air space L. The cables 9 may pass freely out of the boxes 12 from the sheaves 14 and may be guided over upper fixed pulleys 18 and lower movable pulley blocks 19 in a tower 17, counterweights 20 being hung from the lower pulley blocks and the
80 100

cables being fixed at their ends at 21 to the top of the framework.

When gas is withdrawn from the gas holder, the counterweights 20 acting on the cables 9 pull the movable end toward the fixed wall, and the gas pressure in the gas holder is determined by the weight of the counterweights 20.

The lower horizontal edge of the movable end is made gas-tight by the provision of a liquid bath 22 in the well-known manner, but the remaining portion of the edge of the movable end is rendered gas-tight by the employment of a dry seal.

15 The invention is of course not limited to the particular construction herein described and illustrated, since it is capable of modifications within the scope of the appended claims.

I claim:

20 1. A gas holder comprising a horizontally elongated gas container of uniform vertical cross section throughout its length, a wall closing one end of said container and provided with gas inlet and outlet means, a track in the bottom of said container, a closure member in gas-tight relation with the top and sides of said container, said closure member being mounted on said track for movement longitudinally through said container, a liquid seal for gas between the bottom of said closure member and the bottom of said container, and means for urging said closure member along said container in the direction of the closed end of the latter.

35 2. A gas holder comprising a horizontally elongated gas-tight container, a wall closing one end of said container and provided with gas inlet and outlet means, a closure member slideable along said container, a flexible element extending from said closure member through an opening in said end wall, means supporting a body of liquid outside of said container below the opening in the end wall thereof through which said flexible element extends, a sheave within said body of liquid over which said flexible element is trained, a tongue in gas-tight engagement with said end wall above the said opening therein, said tongue extending into said body of liquid whereby gas is prevented from escaping to the atmosphere from said container through the said opening in the end wall thereof, and means outside of said container for exerting a pulling force on said flexible element to urge said closure member towards said end wall.

REINHOLD RICHARD WAGNER.
